Patented Mar. 13, 1962

192,345

HAND VACUUM CLEANER

Lawrence F. Nerheim, Seattle, Wash.
(911 Teaneck Road, Teaneck, N.J.)

Filed July 1, 1960, Ser. No. 61,177

Term of patent 14 years

(Cl. D9—2)

FIG. 1 is a side view of a hand vacuum cleaner, showing my new design;

FIG. 2 is a top plan view thereof;

FIG. 3 is a fragmentary bottom plan view thereof, taken on the right end of FIG. 1;

FIG. 4 is a rear elevational view thereof, and,

FIG. 5 is a front perspective view thereof.

I claim:

The ornamental design for a hand vacuum cleaner, as shown.
